UNITED STATES PATENT OFFICE.

JOHN W. CULP, OF BAY CITY, MICHIGAN, ASSIGNOR TO BATTERY-BALL MFG. CO., OF JACKSON, MICHIGAN, A CORPORATION OF MICHIGAN.

GAME APPARATUS.

1,018,409.

Specification of Letters Patent.

Patented Feb. 27, 1912.

Application filed October 17, 1911. Serial No. 655,202.

To all whom it may concern:

Be it known that I, JOHN W. CULP, citizen of the United States, residing at Bay City, county of Bay, and State of Michigan, have invented certain new and useful Improvements in Game Apparatus, of which the following is a specification.

This invention relates to improvements in game apparatus and more particularly to 10 base ball apparatus.

The objects of this invention are,—First, to provide means for testing the skill of the pitcher and at the same time test the skill of the batter. Second, to provide improved 15 means for registering the results of the play or test. Third, to provide in such a registering apparatus an improved means of controlling the same. Fourth, to provide improved indicating and annunciating means 20 which is largely automatic in its operation, in conjunction with such a game or testing apparatus.

Further objects and objects relating to details and economies of construction will definitely appear from the detailed description to follow.

I accomplish the objects of my invention by the devices and means described in the following specification.

25 The invention is clearly defined and pointed out in the claims.

A structure constituting a preferred embodiment of my invention is fully illustrated in the accompanying drawings forming a 35 part of this specification in which:

Figure I is a perspective view, in broken sections, of my improved apparatus as installed in a large room. Fig. II is an enlarged detail sectional elevation view 40 through the apparatus taken on a line corresponding to line 2—2 of Fig. I, showing the ball curtain or ball target section and its connections and contacts. Fig. III is an enlarged detail sectional view taken on a line 45 corresponding to line 3—3 of Fig. I, showing the "strike" target or section and the "bat" device, and their connected parts and supports. Fig. IV is an enlarged detail view partially in section and in broken section 50 showing the connections for manipulating the "bat" device and connections for its manipulation, the same being taken on a line corresponding to line 4—4 of Fig. V. Fig. V is a detail view partially in section showing the "bat" and bat controlling means taken

on a line corresponding to line 5—5 of Fig. IV, the parts being also in broken section. Fig. VI is an enlarged detail horizontal sectional view taken on a line corresponding to line 6—6 of Fig. III, through the "bat" device and its connections and supports, some parts being in full lines. Fig. VII is an enlarged detail sectional view taken on a line corresponding to line 7—7 of Fig. I, showing the annunciator lamps and their relations and connections generally. Fig. VIII is a detail diagrammatic view of the annunciator system and its wirings, connections and associated parts.

In the drawings similar numerals of reference refer to similar parts throughout the several views and the sectional views are taken looking in the direction of the little arrows at the ends of the section lines.

Considering the numbered parts of the drawings, the target frame 1 is provided for supporting the complete target structure which is supported in a suitable opening 2 in the front thereof. A suitably inclined platform 3 provided with retaining rail 4 is 80 disposed below the target frame to receive the balls that are being played, to facilitate their return to the pitcher. A chute or trough 5 is provided to receive the same, which is inclined upwardly at 6, and is pivoted at 7 to a return trough 9. A lever 8 is secured to the hinged section 6 so that it can be tipped up to pour the balls into the return trough 9. A cord or cable 10 passing over pulleys 11 and 12 is connected to the lever 8 and is provided with a handle 13 at the front end, so that the same can be manipulated by the attendant or by the pitcher when he desires the balls to be returned.

A pitcher's base 14 is provided, of the usual dimension of a pitcher's box, and located at the usual or regular distance in front of the target, which corresponds to the home base in its location. A mat or base 15 is provided for the use of the batter, who stands facing 100 the target structure, so that he can see the direction of the pitched ball in order to manipulate the bat device to hit the same.

A cable is doubled on itself in sections 16 and 17, which play over the floor pulley 18 105 in front of the batter. The section 16 passes over pulleys 19 and 20 to the bat device at the rear of the target frame. The sections 17 passes over pulleys 21 and 22 to the same position. The section 17 passes down to the 110

floor pulley 23 and up in branches 17'-17' connecting to the bat device, and the section 16 into branches 16'-16' and connects to the upper side of the bat device, so that by 5 manipulating the cable the bat can be readily moved up and down at the will of the batter.

An electric cable 24 of suitable wires leads from the annunciator stand 25 to the signal 10 light 26 and connects the various parts of the apparatus with such annunciator and indicator, the details of which will be hereafter fully described.

In the aperture 2 in the front of the casting 1 is a canvas curtain or target section 27, of, the usual dimension, of the area through which the ball would ordinarily be pitched in, pitching a ball, the strike area being in the center thereof. I have denominated this as the ball curtain or section of the target. This is made up of a canvas curtain 27, secured at its upper end to a roller 28 on journal 29, and the lower end is secured similarly to a roller 30 on journal 31. To 25 the upper roller is secured an arm 32 which projects rearwardly, terminating in a contact point 32'. A helical spring 33 puts tension on the arm 32, and is connected to a finger 33' beneath the said arm. A similar 30 arm 35 is secured to the lower roller 30 and has a contact point 35'. A spring 36 connects this arm 35 with finger 36'. The upper contact 32' is disposed to contact with the finger 34 and the lower contact 35' is 35 disposed to contact with the finger 37, which is secured to the wall or the rear of the casting 1, as desired. The levers 32 and 35 are connected by cables 38-39 respectively to the annunciator wire 40, as clearly appears 40 in Fig. II, and the contact fingers 34 and 37 are connected by wires 41-42 to the annunciator wire 43, as also clearly appears in the said Fig. II. The connections to the wires 40 and 43 in the annunciator system 45 will be hereafter explained in conjunction with the particular explanation of the wiring thereof. Whenever a thrown ball strikes the curtain or canvas 27, it will act upon either one or the other of the rollers 28 or 50 30, causing its corresponding lever to close the circuit between the parts and act upon the annunciator by closing the circuit.

In front of the ball curtain or section 27 is disposed a plate 48 of the regulation dimension as a strike section. Whenever a 55 pitched ball hits this section 48, a strike is credited against the batter, whether the batter has moved the bat or not. This strike plate or section 48 is provided with a metallic contact 49 over the back side, and is supported by springs 50-50 yieldingly in position. The contact plate 44 is on the front of the curtain, provided with contact buttons 45-45 for contact with the electrical contact plate 49 on the back of the strike plate

48. The springs 50-50 are arranged so that they do not electrically connect the contacts 44 and 49.

An aperture 46 is through the central portion of the ball section 27 and the plate 44, 70 and a conductor 51 extends therethrough and connects to plate 49. A conductor 47 is secured to the plate 44 and it will be very clear that when the strike section or plate 48 is depressed as by the impact of a pitched ball, it will close the circuit and operate an annunciator, as will be hereinafter described, by closing the circuit which is made up in part of the conductors 47 and 51. The bat support 53 is carried up and down in front 80 of this strike section by suitable rearwardly projecting arms 54 which are disposed in and are free to play up and down in the vertical slots 60 in the curtain or ball section 27, as clearly appears in Fig. I. Laterally projecting branch arms 55 are on the arms 54, which are provided with perforated ears 56 which embrace the vertical guide cables 57-57 at the sides. These vertical guide cables 57 are secured through 90 screw eyes 58 at the bottom and screw eyes 59 at the top, and thus afford guiding support for the said bat device. The sections of cable 16 and 17 are disposed as before indicated, and are provided with branches 16'- 95 16' and 17'-17' respectively, which connect to the top and bottom of these branch arms 55 and serve as the connecting means whereby the batter manipulates the bat device and moves it up and down in front of 100 the strike section of the target.

On the front of the bat support 53 is an insulating plate 62, on the front of which is supported a metallic contact plate 61, which extends the length of the bat device. This 105 bat device is divided into three sections, two end sections 63-63 and a central section 70. Each of the end sections is supported yieldingly in place by a pair of helical springs 65, and is provided with a contact plate 64 110 on its back, which is adapted and disposed to close the circuit with the contact plate 61. Thus whenever either end section of the bat is depressed by the impact of a pitched ball, the circuit embracing conductors 66 and 67 is closed.

On the batting device, the central section 70 is denominated the home run section. It is supported yieldingly in place by coil spring 72 and is provided with a contact 120 plate 71 on its back side. A wire 73 leads through a central aperture 69 in the bat support, out along the back of said support, through the slot 60, as is clearly seen in Fig. VI. It will thus be seen that when the batter succeeds in picking up the pitched ball on the central section 70, so that it receives the impact thereof, he closes the circuit through the conductor 73 and through the conductor 67, as clearly appears in Fig. VI, and actu- 125 130

ates the annunciator, as will be hereafter described.

On the back of the target casing 1 is supported a pair of contacts 74—76 which are connected to conductors 77 and 78 respectively. The contact 74 is provided with a projecting curved portion 75 which is positioned to rest against a movable part of the bat device, as clearly appears in Fig. III, so that when the bat device is in its lowered position, the circuit is open. It will thus be seen that whenever the batter manipulates the device to the extent of moving the bat, he releases this contact 74 and closes the circuit through the conductors 77 and 78, which are connected to the annunciator in a special way that will hereafter be pointed out, to show a strike, and this is associated with the other means so that if the batter hits the ball that appears and if he strikes the center, a home run is indicated. It is seen from a consideration of these devices that the electrical connections are such that they record all of the movements and occurrences that may happen in an ordinary test of the device between the pitcher and the batter. These various circuits are connected into an annunciator device of peculiar construction to accomplish the desired result.

The wiring and annunciator device appears clearly and in diagrammatic and conventional form in Fig. VIII. The annunciator lights appear particularly in Fig. VII, a suitable lens 127 being placed before each light, and the lights are separated from each other by partitions 126. The lights or lenses can of course be of different color, if desired, but that is of no particular consequence so far as my invention here described is concerned. The different annunciator drops and the switches that are indicated in the diagrams are carried on the annunciator stand 25, clearly appearing in Fig. I, which will be readily understood from this description. The lights are arranged within the target frame (see Fig. I).

In order that the structure and operation and the reason for the various parts may be understood, in describing the wiring of the indicating devices, I will describe in that same connection the operation of parts and movement in the different events in the game or test.

Let it be assumed that the pitcher delivers a wild ball which strikes the ball curtain 27. The result is that at some point it will put tension upon one or the other of the rollers 28 or 30 and through their connecting levers will close the circuit. This will cause the current to pass and complete the circuit between the conductors 43—40. When this is done by reference to Fig. VIII, it will be seen that the circuit will be closed through the conductor 79 and through the conductor 81 which embrace the battery or

source of supply 80. The current passes through the coil 82 of the annunciator drop, which releases the drop 83. When the drop 83 is released, as it is connected to the conductor 84 and drops into contact with a contact point on the conductor 92, that circuit is closed and the current passes through the conductor 84 to the light 85, indicating a "ball", through the conductors 86, 87, 88, 89 and 90 to the battery or other source of supply 91, thus completing the circuit. The umpire or referee or counter or master of ceremonies then swings the switch 93, which is connected to conductor 40, to the point 94 of the indicator, which is numbered "1" on the indicator stand 25. When four balls are scored against the pitcher, the switch 93 will, by successive movement, have passed the point 95 to the point 96, and will of course close the circuit through the conductor 40, through the switch 93 through the contact point 96 to the coil 97 of the annunciator drop. This releases the drop 98, which drops against a contact point on the conductor 92, closing that circuit. The current then passes through the conductor 99 through the signal light 100, indicating "base on balls" down through the conductors 87, 88, 89 and 90 to the battery or source of supply 91. It will thus be seen that the signal light "ball" 85 and the signal light 100 indicating "base on balls" will both be illuminated at this time. Let it now be assumed that the pitcher in delivering the ball, hits the strike plate or section 48 and that the batter does not move the bat. When this occurs, it closes the circuit between the conductors 47 and 51 and the current passes along the conductor 101 through the coil 102 of the annunciator drop and releases the drop 103. This closes the circuit because the drop is connected to the conductor 104 and the current passes from the conductor 92 through the conductor 104 to the signal light 105, indicating a "strike." The current then passes down the conductor 87, 88, 89 through the return wire 90 to the battery or source of supply 91. There is also a relay shunt 106 connected to this conductor 104, the relay being located between the conductors 86 and 87, so that when this shunt actuates the relay, the current is broken and the lights and the "ball" and the "base on balls" are shut off, owing to the break by the relay shunt 106. Let it be assumed that the batter, believing he will be able to catch the ball on the bat, manipulates the cable 16—17. As soon as the bat moves, the circuit embracing the conductors 77—78 will be closed and the current will then also be delivered along the conductor 101, actuating the annunciator coil 102 and releasing the drop 103 and securing the same effect that is secured by the striking of the strike plate 130.

or section 48 by a pitched ball when the bat is not moved. Whenever the second strike occurs, the switch 107 is moved onto the point 108 and on the third strike to the point 109, by which current is passed through the coil 110 and releases the drop 111 which closes the circuit. The current passes through the conductor 112 to the "batter out" lamp or signal 113, then down through the conductor 88 and 89 to the conductor 90. Let it be supposed that the batter hits the ball at one end or the other of the bat. The circuit between the conductors 66 and 67 will then be closed and the current will pass along the conductor 114 through the coil 115 of the annunciator drop 116, releasing the drop 116, thereby closing the circuit and passing the current through the conductor 117 to the signal light 118 indicating a "hit", and the current will then pass through the conductor 89 through the conductor 90 to the battery or source of supply 91. There is also a shunt relay 119 which breaks the circuit at this point and cuts off the current leading to the other parts through the signal lights 85, 100, 105 or 113. Let it be supposed also that the batter is particularly fortunate and catches the ball on the central section 70 of the bat. This is a "home run." This will close the circuit by contact of the plate 71 with plate 61, and will close the circuit through the conductors 67 and 73. The current will pass along through the conductor 120 to the coil 121 of the annunciator drop releasing the drop 122 and closing the circuit, passing the current through the conductor 123, which passes to the light 124 indicating "home run," and returns along the conductor 90 to the source of supply. There is also a shunt relay 125 which shuts off the current to all of the remaining indicator lamps above. From this it will be seen that every item of the play is indicated and that this is done practically in an automatic manner by the annunciator system as I have organized it. The annunciator drops are raised to place by the common bar 128 (see Figs. I and VIII) so that the devices are all returned to the initial position by that means at any time at the termination of any particular series of tests.

I have described my improved game apparatus or base ball testing apparatus in the most improved form. However, I desire to comment that the same can be greatly modified without departing from my invention. I believe I have shown structures which respond most effectively to the impact of the ball, but I am aware that various sensitive devices might be provided in this relation. I desire therefore to claim the structure specifically as shown and also broadly. I have organized the structure so that it operates the annunciator system automatically and desire to claim that feature in combination,

although I am aware that mechanical means might be made use of to record the various events as they occur, and I wish the claims to embrace any indicating devices. I thus desire to claim the invention specifically and broadly, as appears by the appended claims. 70

Having thus described my invention, what I claim as new and desire to secure by Letters Patent is: 75

1. In a game apparatus, the combination of a target frame; an outer yielding target section comprising a flexible curtain with vertical slots, rollers therefor, levers connected with the rollers, and electrical contact devices associated with said levers; a centrally disposed yielding target section in front of the said outer target section; electrical contact devices associated therewith; a movable bat bar disposed across the central target section, having rearwardly projecting arms disposed in the vertical slots in the outer yielding target section, a plurality of yielding devices on said bat bar, electrical contact devices associated with said yielding portions; means for manipulating the said bat bar, comprising a cable connected above and below extending to the front of the said target, with suitable guide pulleys therefor, electrical contact devices disposed in the path of movement of said bat bar, in position to be acted upon thereby; electrical conductors leading to the various contact devices and a source of current connected therewith; electric annunciator devices disposed in the electric circuits associated with said contact devices to register the action of the different parts, comprising an annunciator drop for each circuit; relay circuits disposed to be closed by the annunciator drops, signal lights on said relay circuits, relay cut-out magnets disposed in certain of the relay circuits for controlling the current to other of the said circuits; and electric switches with pointers associated to control said circuits in a predetermined manner, all coacting substantially as described and for the purpose specified. 90 95 100 105 110

2. In a game apparatus, the combination of a target frame; an outer yielding target section comprising a flexible curtain with vertical slots, and electrical contact devices associated with said curtain; a centrally disposed yielding target section in front of the said outer target section; electrical contact devices associated therewith; a movable bat bar disposed across the central target section, having rearwardly projecting arms disposed in vertical slots in the outer yielding target section, a plurality of yielding devices on said bat bar, electrical contact devices associated with said yielding devices; means for manipulating the said bat bar, comprising a cable connected above and below extending to the front of the said target, 115 120 125 130

with suitable guide pulleys therefor, electrical contact devices disposed in the path of movement of said bat bar, in position to be acted upon thereby; electrical conductors 5 leading to the various contact devices and a source of current connected therewith; electric annunciator devices disposed in the electric circuits associated with said contact devices to register the action of the different 10 parts, comprising an annunciator drop for each circuit; relay circuits disposed to be closed by the annunciator drops, signal lights in said relay circuits, relay cut-out magnets disposed in certain of the relay 15 circuits for controlling the current to other of the said circuits; and electric switches with pointers associated to control said circuits in a predetermined manner, all coacting substantially as described and for the purpose 20 specified.

3. In a game apparatus, the combination of a target frame; an outer yielding target section comprising a flexible curtain with vertical slots, and electrical contact devices 25 associated with said curtain; a centrally yielding target section disposed in front of the said outer target section; electrical contact devices associated therewith; a movable bat bar disposed across the central target 30 section, having rearwardly projecting arms disposed in vertical slots in the outer yielding target section, a yielding device on said bat bar, electrical contact devices associated with said yielding device; means 35 for manipulating the said bat bar, comprising a cable connected above and below extending to the front of the said target, with suitable guide pulleys therefor, electrical contact devices disposed in the path 40 of movement of said bat bar, in position to be acted upon thereby; electrical conductors leading to the various contact devices and a source of current connected therewith; electric annunciator devices 45 disposed in the electric circuits associated with said contact devices to register the action of the different parts, comprising an annunciator drop for each circuit; relay circuits disposed to be closed by the annunciator drops, signal lights in said relay 50 circuits, relay cut-out magnets disposed in certain of the relay circuits for controlling the current to other of the said circuits; and electric switches with pointers associated to control said circuits in a predetermined manner, all coacting substantially as described and for the purpose 55 specified.

4. In a game apparatus, the combination of a target frame; an outer yielding target section comprising a flexible curtain with vertical slots, and electrical contact devices 60 associated with said curtain; a centrally disposed yielding target section in front of the said outer target section; electrical contact devices associated therewith; a movable bat bar disposed across the central target section, having rearwardly projecting arms disposed in vertical slots in the outer yielding target section, a yielding device on said bat bar, electrical contact devices associated with said yielding device; means for manipulating the said bat bar, comprising a cable connected above and below extending to the front of the said target, with suitable guide pulleys therefor, electrical contact devices disposed in the path of movement of said bat bar, in position to be acted upon thereby; electrical conductors leading to the various contact devices and a source of current connected therewith; electric annunciator devices disposed in the electric circuits associated with said contact devices to register the action of the different parts; relay circuits disposed to be closed by the annunciator devices, signal lights in said relay circuits, and relay cut-out magnets disposed in certain of the relay circuits for controlling the current to other of the said circuits, all coacting substantially as described and for the purpose specified.

5. In a game apparatus, the combination of a target frame; an outer yielding target section comprising a flexible curtain with vertical slots, and electrical contact devices associated with said curtain; a centrally disposed yielding target section in front of the said outer target section; electrical contact devices associated therewith; a movable bat bar disposed across the central target section, having rearwardly projecting arms disposed in vertical slots in the outer yielding target section, a yielding device on said bat bar, electrical contact devices associated with said yielding device; means for manipulating the said bat bar, comprising a cable connected above and below extending to the front of the said target, with suitable guide pulleys therefor, electrical contact devices disposed in the path of movement of said bat bar, in position to be acted upon thereby; electrical conductors leading to the various contact devices and a source of current connected therewith; electric annunciator devices disposed in the electric circuits associated with said contact devices to register the action of the different parts, comprising an annunciator drop for each circuit; relay circuits disposed to be closed by the annunciator drops, signal lights in said relay circuits, relay cut-out magnets disposed in certain of the relay circuits for controlling the current to other of the said circuits, all coacting substantially as described and for the purpose specified.

6. In a game apparatus, the combination of a target frame; an outer yielding target section comprising a flexible curtain with vertical slots, and electrical contact devices associated with said curtain; a centrally disposed yielding target section in front of the

8
said outer target section; electrical contact devices associated therewith; a movable bat bar disposed across the central target section, having rearwardly projecting arms disposed in vertical slots in the outer yielding target section, a yielding device on said bat bar, electrical contact devices associated with said yielding device; means for manipulating the said bat bar, comprising a cable connected above and below extending to the front of the said target, with suitable guide pulleys therefor, electrical contact devices disposed in the path of movement of said bat bar, in position to be acted upon thereby; electrical conductors leading to the various contact devices and a source of current connected therewith; electric annunciator devices disposed in the electric circuits associated with said contact devices to register the action of the different parts; relay circuits disposed to be closed by the annunciator devices, signals in said relay circuits, and relay cut-out magnets disposed in certain of the relay circuits for controlling the current to other of the said circuits, all coacting substantially as described and for the purpose specified.

7. In a game apparatus, the combination of a target frame; an outer yielding target section comprising a flexible curtain with vertical slots, and electrical contact devices associated with said curtain; a centrally disposed yielding target section in front of the said outer target section; electrical contact devices associated therewith; movable bat bar disposed across the central target section, having rearwardly projecting arms disposed in vertical slots in the outer yielding target section, a yielding device on said bat bar, electrical contact devices associated with said yielding device; means for manipulating the said bat bar, comprising a cable connected above and below extending to the front of the said target, with suitable guide pulleys therefor, electrical contact devices disposed in the path of movement of said bat bar, in position to be acted upon thereby; electrical conductors leading to the various contact devices and a source of current connected therewith; electric annunciator devices disposed in the electric circuits associated with said contact devices to register the action of the different parts; and relay circuits disposed to be closed by the annunciator devices, and signals in said relay circuits, all coacting substantially as described and for the purpose specified.

8. In a game apparatus, the combination of a target frame; an outer yielding target section comprising a flexible curtain with vertical slots, and electrical contact devices associated with said curtain; a centrally disposed yielding target section in front of the said outer target section; electrical contact devices associated therewith; a movable

bat bar disposed across the central target section, having rearwardly projecting arms disposed in vertical slots in the outer yielding target section, a yielding device on said bat bar, electrical contact devices associated with said yielding device; means for manipulating the said bat bar, comprising a cable connected above and below extending to the front of the said target, with suitable guide pulleys therefor, electrical contact devices disposed in the path of movement of said bat bar, in position to be acted upon thereby; electrical conductors leading to the various contact devices and a source of current connected therewith; electric annunciator devices disposed in the electric circuits associated with said contact devices to register the action of the different parts, all coacting substantially as described and for the purpose specified.

9. In a game apparatus, the combination of a target frame; an outer yielding target section comprising a flexible curtain, and electrical contact devices associated with said curtain; a centrally disposed yielding target section in front of the said outer target section; electrical contact devices associated therewith; a movable bat bar disposed across the central target section; a yielding device on said bat bar, comprising a cable connected above and below extending to the front of the said target, with suitable guide pulleys therefor, electrical contact devices disposed in the path of movement of said bat bar, in position to be acted upon thereby; electrical conductors leading to the various contact devices and a source of current connected therewith; electric annunciator devices disposed in the electric circuits associated with said contact devices to register the action of the different parts, all coacting substantially as described and for the purpose specified.

10. In a game apparatus, the combination of a target frame; an outer yielding target section; a centrally disposed yielding target section in front of the said outer target section; a movable bat bar disposed across the central target section; a yielding device on said bat bar; means for manipulating the said bat bar, comprising a cable connected above and below extending to the front of the said target, with suitable guide pulleys therefor; electric annunciator devices connected to be operated by the depression or movement of said parts, coacting substantially as described and for the purpose specified.

11. In a game apparatus, the combination of a target frame; an outer yielding target section; a centrally disposed yielding target section in front of the said outer target section; a movable bat bar disposed across the

- central target section; a yielding device on said bat bar; means for manipulating the said bat bar; and electric annunciator devices connected to be operated by the depression or movement of said parts, coacting substantially as described and for the purpose specified.
12. In a game apparatus, the combination of a target frame; an outer yielding target section; a centrally disposed yielding target section in front of the said outer target section; a movable bat bar disposed across the central target section; means for manipulating the said bat bar; and electric annunciator devices connected to be operated by the depression or movement of said parts, coacting substantially as described and for the purpose specified.
13. In a game apparatus, the combination of a target frame; an outer yielding target section; a centrally disposed yielding target section in front of the said outer target section; a movable bat bar disposed across the central target section; a yielding device on said bat bar; means for manipulating the said bat bar; and means of indicating the individual action or movement of said parts, for the purpose specified.
14. In a game apparatus, the combination of a target frame; a yielding target; a movable bat bar disposed across the yielding target; a yielding device on said bat bar; means for manipulating the said bat bar; and means of indicating the individual action or movement of said parts, coacting for the purpose specified.
15. In a game apparatus, the combination of a target frame, an outer yielding target section, a centrally-disposed yielding target section, a movable bat bar disposed across the central target section, means for manipulating said bat bar, a yielding central section for said bat bar, and annunciators with circuit closers disposed to be acted upon by the various movable and yielding parts to register the action thereof, coacting for the purpose specified.
16. In a game apparatus, the combination of a target frame, an outer yielding target section, a centrally-disposed yielding target section, a movable bat bar disposed across the central target section, means for manipulating said bat bar, and annunciators with circuit closers disposed to be acted upon by the various movable and yielding parts, to register the action thereof, coacting for the purpose specified.
17. In a game apparatus, the combination of a target frame, an outer target section, a centrally disposed target section, a movable bat bar disposed across the central target section, and means for manipulating said bat bar, coacting for the purpose specified.
18. In a game apparatus, the combination of a target frame, an outer yielding target section comprising a flexible curtain, rollers therefor, levers connected with the rollers, and electrical contact devices associated with said levers, as described.
19. In a game apparatus, the combination of a target frame, an outer target section, a centrally disposed target section in front of the said outer target section, a movable bat bar disposed across the central target section, and means for indicating the individual actions of each, as described.
20. In a game apparatus, the combination of a target frame, an outer yielding target section, a centrally disposed yielding target section in front of said outer target section, a movable bat bar disposed across the central target section, a yielding device on said bat bar, means for manipulating the said bat bar, electric circuits with contact devices disposed to be acted on by said parts, electric annunciator devices disposed in the electric circuits associated with said contact devices to register the action of the different parts, comprising an annunciator drop for each circuit, relay circuits disposed to be closed by the annunciator drops, signals in said relay circuits, relay cut-out magnets disposed in certain of the circuits for controlling the current to other of the said circuits, and electric switches with pointers associated to control said circuits, all coacting substantially as described and for the purpose specified.

In witness whereof, I have hereunto set my hand and seal in the presence of two witnesses.

JOHN W. CULP. [L.S.]

Witnesses:

RUSSELL B. THAYER,
GERTRUDE SMALLING.
